[57] **CLAIM**

The ornamental design for a milling cutter insert for fine milling, as shown and described.

DESCRIPTION

FIG. 1 is a top perspective view of the milling cutter insert for fine milling showing our new design;

FIG. 2 is a top view thereof, the bottom view being a mirror image of the top view, except that it is rotated 90°;

FIG. 3 is a right-side view of FIG. 2 left-side view being a mirror image of the right-side view; and,

FIG. 4 is a side view taken from the lower edge of FIG. 2 the upper edge being a mirror image thereof.
